C. MAXON

LATCH

Filed Aug. 20, 1926

FIG. 2

FIG. 5

INVENTOR.
CURTIS MAXON

BY

R. W. Smith
ATTORNEY.

UNITED STATES PATENT OFFICE.

CURTIS MAXON, OF SAWTELLE, CALIFORNIA.

LATCH.

Application filed August 20, 1926. Serial No. 130,412.

This invention relates to latches of the type controlled by a push button movable perpendicularly to a supporting surface through a knob mounted on the surface; and 5 it is the object of the invention to provide a simplified and practical mounting for the control mechanism which eliminates the use of fastening screws or the like, so as to adapt the construction to a knob of glass or 10 other frangible material, and it is a further object of the invention to provide for convenient adjustment of the mounting for the control mechanism so as to readily adapt it to doors or the like of different thickness. 15 The operating control is particularly adapted for use in connection with the bolt mechanism of a latch such as shown in my U. S. Patent No. 1,571,453, of Feb. 2, 1926; and it is a still further object of the invention to simplify the operating mechanism of my said prior patent and adapt it for 20 convenient manufacture at minimum expense.

The invention will be readily understood from the following description of the accompanying drawings, in which:

Fig. 1 is a horizontal section through the latch mounted on a cupboard door.

Fig. 2 is a side elevation of the latch operating means with the parts disassembled.

30 Figs. 3 and 4 are transverse sections on the lines 3—3 and 4—4 of Fig. 1.

Fig. 5 is a fragmentary front elevation of a cupboard door, with the improved latch mounted thereon.

35 The latch operating mechanism forming the subject matter of the present invention is illustrated as mounted in a bore 1 extending through a cupboard door 2 which seats in a frame 3, the operating means controlling a bolt mechanism for the latch which is mounted on the inner surface of the door with the bolt preferably adapted for sliding movement parallel to the surface of the door so as to project and retract the bolt relative to a cooperating catch 4 mounted on frame 3.

A casing 5 for the bolt mechanism has an opening in its base overlying the inner end of bore 1, and a bolt 6 slidable in the casing 50 is normally projected for engaging catch 4 by means of a spring 7. The means for retracting the bolt against the tension of its spring so as to disengage catch 4, comprises an

arm 8 projecting transversely from the bolt in casing 5, and extending through the opening in the base of the casing into the bore 1. The arm 8 is engaged by an operating rod 9 of the control mechanism for the latch, said operating rod being adapted for axial movement in bore 1 in alignment with arm 8, 55 with the cooperating ends 10 of the arm and rod inclined relative to the direction of movement of both the rod 9 and bolt 6 as shown in Fig. 1, so that when the rod is pushed inwardly the arm 8 is shifted laterally relative to the rod for retracting the bolt.

The control mechanism for the latch, of which the rod 9 is the actuating means, overlies the outer end of bore 1, and comprises 60 a knob 12 for manually swinging door 2 and a push button 13 slidable in the bore 14 of the knob for shifting rod 9 so as to retract bolt 6. The knob and push button are mounted on door 2 without the use of fastening screws or the like, so that the elimination of openings through the knob for such fastening means permits the knob being inexpensively constructed of glass or other frangible material; and the mounting for 65 the knob and push button also provides for ready adjustment to secure the parts in place and adapt the rod 9 for engaging arm 8, irrespective of variations in the thickness of door 2. As an instance of this arrangement, a barrel 15 is adapted for projection through the bore of knob 12, with an exterior peripheral flange 16 at the outer end of the barrel adapted for abutment against the outer end of the knob for limiting inward movement of the barrel. An interior peripheral flange 17 is also provided at the outer end of barrel 15, and the push button 13 is insertable through the inner end of the barrel with an enlarged base 18 of the push button adapted for abutment against the flange 17 to limit outward movement of the push button when its head projects beyond knob 12 just sufficiently to permit it being pushed inwardly by the finger.

The push button is adapted to be moved inwardly relative to barrel 15 and knob 12, but is preferably held against rotation by a key 19 stamped in the surface of the barrel and engaging a cooperating keyway 20 in the base of the push button. The push button

is normally projected to position for operation by the finger, by means of a coil spring 21 in barrel 15 engaging the base 18 of the push button and abutting against a washer 5 22 in the inner end of the barrel, the washer being preferably held in place by crimping the end of the barrel over the same.

The barrel 15 is of a length to project beyond the inner end of knob 12 into the bore 1 with the flanged inner end of the knob abutting against the door 2, and the operating rod 9 extends into barrel 15 through washer 22 and the coil spring 21, with the inner end of the rod threaded into push button 13 as shown at 23.

The knob assembly as thus described is held in place on the door by means of a sleeve 25 insertable in the inner end of bore 1 before the casing 5 is mounted in place, 20 the sleeve having a flanged end 26 adapted to engage the inner end of bore 1, with the opposite end 27 of the sleeve adapted for threaded engagement on the threaded inner end 28 of barrel 15, so as to clamp the knob 12 between flange 16 and the outer surface 25 of door 2 and also secure the barrel 15 and its associated parts.

The inner end 28 of barrel 15 is preferably threaded for an appreciable length, and 30 the inner end of the bore of knob 12 is preferably countersunk as shown at 30 to adapt it for the reception of the inner end of sleeve 25, so that the sleeve may be tightened up on the barrel as far as necessary to clamp 35 the mechanism on doors of different thickness.

In order to screw the sleeve 25 onto the barrel 15, the flanged outer end 26 of the sleeve is preferably notched as shown at 31, 40 and a tool 35 shown in Fig. 2, is provided with pins 32 adapted for reception in sleeve 25, with shoulders 33 of the pins engaging the notches, so that the tool is adapted to rotate the sleeve and is held against lateral 45 displacement. When the operating mechanism is assembled, and before casing 5 is mounted in place, it is also necessary to adjust rod 9 relative to push button 13 so that the cooperating surfaces 10 will be in operative 50 relation, and for this purpose the opposite end of tool 35 is notched as shown at 34 to correspond to the end of rod 9, so that the tool may be used for turning the rod to provide the desired longitudinal and rotatable 55 adjustment.

I claim:

1. A latch comprising a bolt, a support having an opening therethrough, a barrel extending into one end of said opening, an 60 operating rod movable in said barrel, cooperating abutments on the bolt and rod for shifting the bolt by movement of the rod, and a sleeve extending into the opposite end

of said opening and engaging the barrel for fixing the same relative to the support. 65

2. A device of the character described adapted for mounting on a support having an opening therethrough, comprising a barrel extending into one end of said opening and having abutment means at its outer end, 70 an operating rod movable in said barrel, a knob on the barrel between said abutment means and the surface of the support, and a sleeve extending into the opposite end of 75 said opening and engaging the barrel for fixing the sleeve and knob relative to the support.

3. A device of the character described adapted for mounting on a movable support having an opening therethrough, comprising a barrel extending into one end of the opening, means for latching the support, an operating rod for the latching means movable in said barrel, and a sleeve extending 80 into the opposite end of said opening and 85 engaging the barrel for fixing the same relative to the support, the outer end of the sleeve and the adjacent end of the operating rod being adapted for engagement by a key 90 for rotatably adjusting said parts relative to the barrel.

4. A device of the character described adapted for mounting on a movable support having an opening therethrough, comprising a barrel extending into one end of said opening and having abutment means at its outer end, a push button slidable in the barrel and having a shoulder engaging said abutment means for limiting the projection of the push button beyond the outer end of the 100 barrel, means for latching the support, an operating rod for the latching means fixed to said push button and projecting beyond the inner end of the barrel, spring means tending to retract the operating rod and 105 project the push button beyond the outer end of the barrel, and a sleeve extending into the opposite end of said opening and engaging the barrel for fixing the same relative to the support. 110

5. A device of the character described adapted for mounting on a movable support having an opening therethrough, comprising a barrel extending into one end of the opening, a push button adapted for axial movement in said barrel but held against rotation therein, means for latching the support, an operating rod for the latching means fixed to the push button and projecting beyond the inner end of the barrel, and a sleeve extending into the opposite end of said opening and engaging the barrel for fixing the same relative to the support. 115 120

In testimony whereof he has affixed his signature to this specification.

CURTIS MAXON.
